UNITED STATES PATENT OFFICE.

PETER IVERSEN LANGLYKKE, OF CHICAGO, ILLINOIS, ASSIGNOR TO HAGGARD & MARCUSSON COMPANY, OF CHICAGO, ILLINOIS, A CORPORATION OF ILLINOIS.

SPRING BED-BOTTOM.

1,279,715.

Specification of Letters Patent. Patented Sept. 24, 1918.

Application filed June 26, 1917. Serial No. 176,992.

To all whom it may concern:

Be it known that I, PETER IVERSEN LANGLYKKE, a citizen of the United States, and a resident of the city of Chicago, county of Cook, and State of Illinois, have invented 5 certain new and useful Improvements in Spring Bed-Bottoms, of which the following is a specification.

My invention relates to improvements in 10 wire fabric designed for use in spring bed-bottoms, and has for its object the production of a fabric of this character which will be of durable and economical construction and which will afford the desired resiliency 15 for comfort.

A further object is the production of a 20 fabric as mentioned, which will be non-sagging in character; that is a fabric in which, when used in a bed-bottom, the occupation 25 of one portion of the bed-bottom will not cause sagging of other portions of the bed-bottom.

Other objects will appear hereinafter.

The invention consists in the combinations 25 and arrangements of parts hereinafter described and claimed.

The invention will be best understood by reference to the accompanying drawings, forming a part of this specification, and in 30 which,

Figure 1 is a top plan view of a bed-bottom, embodying the invention,

Fig. 2, a longitudinal section of the bed-bottom,

Fig. 3, an enlarged transverse section of the bed-bottom, and

Fig. 4, an enlarged fragmental plan view of a form of the construction designed to produce a non-sagging bed-bottom.

40 The preferred form of construction, as illustrated in the drawings, comprises a bed-bottom consisting of a rectangular frame 5 and a fabric connected therewith, said fabric being engaged at its ends with the upwardly extending flanges of angle irons 6 which form the end bars of the frame. In 45 the connection of the fabric with the bars 6, helical tension springs 7 are employed, as is customary, which lend yieldability or resiliency to the bed-bottom.

The fabric comprises a plurality of spaced apart parallel longitudinally extending cables, each of which is formed of a pair of co-extensive wire strands 8. Said cables are 55 connected at intervals by transversely ex-

tending links 9. The ends of links 9 engage with loops 10 which are formed at intervals in said cable, said loops being produced by twisting the cable strands together at intervals to form substantially unyielding eyes 60 66 10. In order to insure against unwrapping or unwinding of the cable strands through pressure applied at the eyes or loops 10 by the links 9, when the bed-bottom is in use, the cable strands at opposite sides of each eye are oppositely twisted, it being seen that with this arrangement a secure hitch or interlocking is effected at opposite sides of each eye which will positively prevent unwrapping or unwinding of the cable strands. 70

At the same time, this peculiar twisting of the cable strands is very easily produced, inasmuch as the wires, in the formation of the cable, are turned first in one direction and then in the other, instead of continuously in 75 one direction as is ordinarily done in twisting two wires together, leaving parallel spaced-apart portions 8-8 between adjacent eyes. The links at the longitudinal edges of the fabric engage with perforated spring 80 metal strips 11, connected at their ends with the bar 6 in the same manner as the ends of the cables. The ends of the cable strands project into the adjacent ends of the springs 7, as clearly seen in Figs. 2 and 4, to protect 85 the same, said springs, at the same time serving to hold the strand ends against unwrapping or untwisting.

Where it is desired to produce a non-sagging bed-bottom, that is one in which, when 90 one portion of the bed is occupied, the other portion of the bed-bottom will remain perfectly straight and horizontal and unaffected by the occupied portion thereof, the number of links 9 employed in the bed-bottom will be reduced fifty per cent. so that 95 the links at opposite sides of each cable will be in staggered relation, as seen in Fig. 4. With this arrangement, it will be seen that the bed-bottom is rendered laterally yieldable 100 so that a sagging of or pressure applied to one side of the bed will not be transmitted to the other side or portion of the bed.

While I have illustrated and described the 105 preferred forms of construction for carrying my invention into effect, these are capable of variation and modification without departing from the spirit of the invention. I, therefore, do not wish to be limited to the precise details of construction set forth, but 110

desire to avail myself of such variations and modifications as come within the scope of the appended claims.

Having described my invention what I claim as new and desire to secure by Letters Patent is:

1. A spring bed-bottom fabric comprising a frame, having end rails; a plurality of helical springs spaced-apart and connected 10 at intervals to each end rail; a plurality of spaced-apart parallel cables, comprising a pair of wires twisted together at their ends and connected to said helical springs with the twisted ends of said cables contained 15 within the coils of said springs and engaging the interior surface of the springs.

2. A spring bed bottom fabric comprising a plurality of spaced-apart parallel cables, each extending substantially the full length 20 of the bed bottom and each connected at its

opposite ends to helical springs; links connecting adjacent cables together at intervals; each cable comprising two wires spaced apart between eyes formed therein at intervals to receive the links, said eyes formed 25 by twisting the separated wires in opposite directions on each side of the respective eyes to an extent to prevent separation of the wires when stress is applied thereto; the ends of said cables, beyond the terminal eyes 30 separated to bear against the interior of the helical springs to prevent separation of the wires at the terminal twists.

In testimony whereof I have signed my name to this specification in the presence of 35 two subscribing witnesses.

PETER IVERSEN LANGLYKKE.
